UNITED STATES PATENT OFFICE

REGINALD C. SHAND, OF PIEDMONT, CALIFORNIA

HOSE RACK

Application filed August 1, 1927. Serial No. 209,796.

This invention relates generally to supports and more particularly to a rack for supporting a fire hose.

It is an object of this invention to devise an improved device for supporting a folded hose whereby it may be quickly and conveniently removed.

It is a further object of this invention to devise a hose rack utilizing a pair of movable side bars, in which means will be provided to insure positive disengagement of the loops of folded hose, when the bars are unlocked.

It is a further object of this invention to devise a fire hose rack which will be cheap to manufacture and will be simple in construction, and which may be readily mounted on a water pipe without danger of impairing its normal operation.

Further objects of this invention will appear from the following description in which I have set forth the preferred embodiment of my invention. It is to be understood that the invention is to be accorded a range of equivalents consistent with the state of the prior art.

25 Referring to the drawing:

Figure 1 is a side elevational view illustrating a complete hose rack constructed in accordance with this invention.

30 Fig. 2 is a cross sectional view taken along the line 2-2 of Fig. 1.

Fig. 3 is a cross sectional view taken along the line 3-3 of Fig. 1.

35 Fig. 4 is a cross sectional view taken along the line 4-4 of Fig. 1.

The invention may be outlined briefly as utilizing a pair of side bars between which the loops of a folded hose are normally retained. These bars have pivotally connected ends so that at least one bar may swing away from the other bar, and have their free ends adapted to be locked together by the nozzle of the hose. The inner faces of the bars are provided with a plurality of lugs which are normally adapted to engage the hose loops, and these lugs are constructed in a novel manner in order to insure their positive disengagement from the hose when the side bars are unlocked.

50 Referring to the drawing for a more complete description, there is shown a pair of

side bars 10 and 11 which are normally retained in substantially a horizontal position. For convenience it is preferable to support these bars by means of the water pipe to which the fire hose is normally connected, and for this purpose I have shown one end of bar 11 as provided with a collar 12, this collar having a circular opening 13 which is adapted to fit over the projecting end of the water pipe 14. The axis of opening 13 is 55 preferably arranged at an angle of slightly less than 90 degrees with respect to the plane of bars 10 and 11 as shown in Fig. 1 whereby when positioned upon the water pipe, bars 10 and 11 will be practically horizontal. Collar 12 is normally clamped upon the pipe as by means of the flanges 16, whereby the bar 11 is maintained in fixed substantially horizontal position. The bars 10 and 11 are movable relative to each other and for this purpose are preferably pivotally connected together. For example there is shown a pivotal connection formed by providing a pair of spaced apertured lugs 17 upon one side of collar 12, between which is disposed an apertured bearing portion 18 which is formed on one end of bar 10. Pivot pin 19 extends thru apertured lugs 17 and bearing portion 18. The location of pivot pin 19 is preferably adjacent one side of collar 12, so that 70 side bar 10 may be substantially a straight member, thus simplifying and cheapening its manufacture.

Attached to the water pipe 14 there is shown the usual fire hose 21 which normally is in 85 folded position and is adapted to be detachably retained by the bars 10 and 11. The end of the hose is provided with a nozzle 22 of the usual construction, and this nozzle is preferably utilized for normally locking the bars 90 10 and 11 together. Thus the free end of bar 10 is provided with an extension 23 which has a slot 24, and the free end of bar 11 has a similar slotted extension 26. The extensions 23 and 26 are offset vertically so that with the bars 10 and 11 in normal position, the extensions are in superposed relationship with their respective slots alined. The nozzle is 95 normally disposed within these slots and is supported by the upper extension 23. There- 100

fore for the normal position of the nozzle the bars 10 and 11 are locked together in fixed spaced relationship, but when the nozzle is removed bar 10 is free to swing away from bar 11. The slots in extensions 23 preferably have straight parallel sides so that the nozzle may be readily removed without contracting the side bars 10 and 11.

As previously explained the bars 10 and 11 are adapted to detachably retain the hose 21. Normally this hose is folded to form a plurality of vertical loops 28 and these loops are adapted to be engaged and supported by a series of lugs 29 which project from the inner face of the bars 10 and 11. These lugs preferably each have an upper surface 31 inclined downwardly as shown in Fig. 3, and also have one side 32 thereof inclined forwardly toward the free end of the bars, as shown in Fig. 2. This inclination of the surfaces of these lugs facilitates disengagement of the hose therefrom as will be presently explained. Adjacent the free end of each side bar there is provided a lug 33 which extends inwardly substantially farther than the lugs 29. These lugs 33 are preferably in the form of V-shaped projections as shown in Figs. 1, 2 and 4. The upper surface 34 of each projection is inclined downwardly as shown in Fig. 4 and the entire lug is inclined from the vertical as shown in Fig. 1, so that the surface 34 which engages the foremost loop of the hose, is not only inclined downwardly but also inclined forwardly toward the free end of bars 10 and 11.

In operation, the hose is folded and the loops are engaged with the lugs 29 as shown in Fig. 1. The loop nearest the free end of bars 10 and 11 is engaged with the large lugs 33. The nozzle 22 is normally engaged and supported by extensions 23 and 26 so that the bars 10 and 11 are locked in fixed spaced relationship. If an operator desires to use the hose, he need merely remove the nozzle 22, and the weight of the hose upon the inclined upper surfaces of lugs 29 and 33, will generally be sufficient to cause the bar 10 to move outwardly so that these lugs are disengaged from the hose and the hose is permitted to drop. In some cases there may be sufficient friction in the pivotal connection for bar 10, or the lugs may stick to the hose so that when nozzle 22 is removed the bars 10 and 11 will not automatically move apart. In this case if the operator merely pulls upon the end of the hose, the downwardly and forwardly inclined upper surfaces 34 of the lugs 33 will forcibly move the bar 10 outwardly and cause all of the lugs 29 to be disengaged from the hose loops. If the end lugs 33 were not made substantially longer than the lugs adjacent the pivotally connected ends of the side bars, then any tension exerted upon the end of the hose to disengage the same might merely move the side bars apart sufficiently to dis-

engage only a part of the lugs 29. However by making the lugs 33 comparatively long as shown, all of the hose is immediately disengaged with disengagement of lugs 33 and all of the hose is permitted to drop. If any of the hose loops still stick upon the smaller lugs 29, they may be readily pulled loose by virtue of the inclined side surfaces 32.

The separate pivotal connection for the side bar 10, is to be preferred to a construction which utilizes the water pipe as a pivotal connection member, since by this construction tightening of the flanges 16 can never impair free pivotal movement of bar 10. Furthermore rust and corrosion are not apt to attack and affect the operation of such a separate pivot whereas a pivotal connection such as shown in the Jones Patent 927,410 is apt to rust fast when not used over long periods.

I claim:

1. In a hose rack, a pair of side bars having pivotally connected ends, disengageable means for locking together the free ends of the bars, and a series of lugs projecting from the inner face of each bar for engaging and supporting the loops of a folded hose, the lug adjacent the hinged end of each bar being substantially shorter than the lug adjacent the locked end, said latter lug on each bar having a downwardly and forwardly inclined hose engaging surface whereby engagement of the hose with said latter lugs tends to move the bars apart.

2. In a hose rack, a pair of side bars, means for detachably retaining a hose between said bars, a collar on the end of one of said bars, said collar being adapted to surround a water pipe whereby said bar is supported in substantially horizontal position, a pivot pin connecting one end of the other bar to the collar, a series of tapered lugs on the inner face of each bar, the lug of each bar adjacent the free end of the same being substantially longer than the lug adjacent the hinged end, said lugs serving to engage and support the loops of a folded hose, and means for locking together the free ends of said bars, said means including slotted end portions on each of the bars adapted to be superposed with the slots in registry in the locking position of the bars.

In testimony whereof, I have hereunto set my hand.

REGINALD C. SHAND. 120
